UNITED STATES PATENT OFFICE.

GEORGE EVERETT, OF PORTERVILLE, CALIFORNIA.

SMOKER'S PIPE.

1,056,982.

Specification of Letters Patent. Patented Mar. 25, 1913.

Application filed May 7, 1912. Serial No. 695,646.

To all whom it may concern:

Be it known that I, GEORGE EVERETT, a citizen of the United States, residing at Porterville, in the county of Tulare and State of California, have invented new and useful Improvements in Smokers' Pipes, of which the following is a specification.

This invention relates to smokers' pipes.

The object of the present invention is to provide a smoker's pipe involving details of construction, having in view the function of protecting the smoker's mouth from injurious contact with by-products of combustion of tobacco in the pipe, the latter being provided with members so perforated and chambered as to collect and condense material during the combustion of the tobacco, and designed with the view of avoiding the possibility of particles of tobacco from passing from the bowl of the pipe through the stem.

A further object of the invention is to provide a pipe of sectional construction, the sections being designed for ready removal and thorough cleansing.

The invention consists of the parts and the combination and construction of parts, as hereinafter more fully described and claimed, having reference to the accompanying drawings, in which—

Figure 1 is a longitudinal vertical section through the improved pipe. Fig. 2 is a view of the bowl end of the central section. Fig. 3 is a view of the stem end of the central section.

In its illustrated embodiment my invention consists of a suitably shaped and sized bowl 2, having the usual tobacco receiving chamber 3, and from the lower portion of this chamber there is led a plurality of downwardly projecting passage-ways 4, terminating in the collection chamber 5, the lower end of which is sealed with a closure or removable button or stopper 6. The condensing chamber 5 is formed in a rearwardly extending part 7 of the bowl, to which is suitably connected, as by a screw threaded stem 8, a body or section 9 of suitable length and diameter, the opposite end of which is provided with a screw 10 whereby it may be detachably secured to the mouth piece or stem 11. The stem is longitudinally perforated as at 12, and this perforation coincides with a central perforation

designated as *i*, extending substantially throughout the central section 9 of the pipe, but the flue *i* terminates adjacent the front end of the body 9, being closed by a transverse wall 13 on the opposite side of which is formed a conduit 14, intersecting with the upper portion of the condensing chamber 5 of the pipe bowl.

Since the transverse wall 13 of the pipe section 9 is interposed between the chamber 5 and the stem opening 12, I have provided the central body portion 9 of the pipe with a series of flues or passage-ways extending from end to end therein, the passage-ways being so cross-connected as to form a continuous circuitous pass through which the fumes of combustion may be exhausted from the pipe bowl through the mouth piece 11, and the arrangement of the circuitous passage-ways in the body 9 of the pipe will be readily understood by referring to Fig. 2, in which there is indicated at *a* a longitudinally extending opening which communicates at its forward end with the conduit 14 in the stem 8, from which fumes of combustion will be drawn through the duct *a* lengthwise of the pipe section 9, whence it will flow downwardly toward the rear end of the section through a vertical transverse channel *b*, connecting with a lower longitudinally extending duct *c*, through which the smoke will be drawn forwardly, thence transversely across the pipe section 9 through a short channel *d*, which communicates with a longitudinal bore or duct *e*, through which the smoke will travel rearwardly through the body or section 9, entering a cross-duct *f* at the rear end of the section 9, thence flowing into a longitudinal passage-way *g*, through which the smoke is conducted forwardly and from thence through a diagonal port 8, from which it is delivered into the central flue *i* which registers with the stem bore 12. The end passage-ways *b* and *f* at the rear end of the body section 9 are formed by slightly recessing the end wall of the section, and when the mouth piece 11 is assembled in position it effectually closes the transverse passage-ways *b* and *f* so that the smoke is compelled to traverse these passage-ways when entering the longitudinal ducts. The forward end of the pipe section 9 is formed with a transverse duct or passage-way *d* which is

recessed in the end of the section 9, and is closed by the assembling of the bowl body to the body section 9.

The smoke passages 4 in the bowl will 5 greatly reduce the suction while smoke is being drawn from the chamber 3, and this greatly reduces the possibility of drawing pieces of tobacco from the bowl which is so common in the ordinary pipe, then when 10 the smoke enters the chamber 5 it is cooled to a considerable extent on account of this chamber being so much larger than the other smoke passages. The chamber 5 acts in another capacity in that since it is much 15 larger than the combined area of the openings 4, and by reason of its vertical position in the bowl body in case any pieces of tobacco are drawn into the collecting chamber 5, they cannot be drawn from this into 20 the flue section 9 or the stem 11 because on account of the volume of the chamber 5 the suction in it will not be great enough to lift particles of material in the same; and also by reason of the cooling of the smoke 25 in the chamber 5 the nicotine moisture is condensed to a great extent and will be deposited in the chamber and prevented from entering the circuitous flue in the section 9. The smoke drawn from the condensing 30 chamber 5 is considerably cooled by passing through the circuitous passage-ways in the pipe section 9, and since the several passage-ways in the pipe elements are all substantially of straight form without sharp curves 35 or corners, by simply disconnecting the members of the pipe these passage-ways may be most effectually and readily and thoroughly cleansed.

It is one of the main objects of this pipe 40 to provide the equivalent of a long stem pipe in a small convenient sized article, which can be easily carried in the pocket. It is well known that smokers prefer a long 45 stemmed pipe for the reason that smoke and fumes of combustion are reduced in temperature so as to be more agreeable, as when a long stem pipe is used, and by the present invention the formation of the circuitous passage-ways provides a pipe of smaller size 50 giving substantially the same results as a long stem pipe.

Having thus described my invention, what

I claim and desire to secure by Letters Patent is—

1. A smoker's pipe having a bowl provided with a combustion chamber, a substantially vertical condensing chamber out of line with the combustion chamber, said bowl having a plurality of ducts connecting said chambers and said vertical chamber having substantial length and being larger than the combined area of said ducts to prevent particles of tobacco being sucked out of the condensing chamber, a removable plug in the bowl member whereby access may be had to the condensing chamber, a mouth piece, and a section interposed between the bowl and the mouth piece, said section being provided with circuitous straight passage-ways forming a continuous flue connecting the condensing chamber with an aperture of the mouth piece.

2. A smoker's pipe having a bowl provided with a combustion chamber, a condensing chamber, said bowl having a plurality of ducts connecting said chambers, a removable closure permitting access to the condensing chamber, said condensing chamber having substantial length and being larger than the combined area of said ducts whereby particles of tobacco entering the condensing chamber will be retained therein, a mouth piece having a longitudinal flue, and a central detachable body section provided with a plurality of parallel longitudinally extending passage-ways, some of which are cross-connected, said section having a substantially continuous central flue divided by a transverse wall, said central flue being connected at one end in front of the transverse wall to one of the longitudinal flues, and the central flue being connected behind the transverse wall to another of the longitudinal flues, the flues of the central section forming a continuous circuitous passage-way communicating with the mouth piece.

In testimony whereof I have hereunto set my hand in the presence of two subscribing witnesses.

GEORGE EVERETT.
